UNITED STATES PATENT OFFICE

2,509,024

AUTOMATIC RECLOSED ELECTRIC
CIRCUIT INTERRUPTER

Ludwig S. Walle, Lansdowne, Pa., assignor to
General Electric Company, a corporation of
New York

Application July 12, 1949, Serial No. 104,297

5 Claims. (Cl. 200—122)

1

My invention relates to electric circuit interrupters of the automatic reclosing type, and more particularly to a circuit interrupter of the aforesaid type wherein the reclosing operation is delayed for a predetermined time and the interrupter is locked in open circuit position after a predetermined number of consecutive reclosures in the event that the fault still remains.

In certain power areas of large electrical power transmission systems, such as for example suburban and rural areas, power is transmitted by a single phase line which is quite generally protected by fuses. These lines, which may operate under a tension up to 15,000 volts, for example, often extend through wooded areas where short circuit possibilities, due to falling tree limbs, etc., are comparatively high. In case of a short circuit under such conditions, the line may be cut out of operation by the fuse for an appreciable length of time depending upon the replacement of the fuse by the maintenance crew.

As is well known, the percentage of temporary or momentary short circuits in modern electric power transmission systems is comparatively high, so that in a large majority of the cases immediate reclosure of the circuit restores service.

However, on a comparatively low power single phase extension, reclosing circuit breaker systems have not been used due to the prohibitive cost of such installations.

Therefore, it is an object of my invention to provide an improved automatic reclosing circuit interrupter which is simple, compact, and economical in construction and efficient in operation, and which is especially well adapted for use in isolated locations.

My invention, therefore, consists essentially of an oil filled interrupter employing current conductive thermally responsive elements which, under overload conditions, effect an initial contact separation, thus initiating an arc, the heat of the arc causing oil vapor formation, the pressure of which further increases the contact separation, thus extinguishing the arc, and a lockout mechanism employing a thermostatically responsive element which is operative after a number of reclosures and interruptions of a subsisting fault to lock the interrupter in open circuit position.

In accordance with a preferred embodiment of my invention, a simple and compact automatic reclosing circuit breaker is incorporated in a single unit which may be suitably mounted, such as by suspension from a wooden cross arm of the power line pole, and cut directly into the line.

2

The circuit breaker is arranged automatically to reclose for a predetermined number of consecutive operations, after which the breaker is locked in open circuit position. A suitable time delay is present in each reclosing operation without the use of complicated clockwork time delay mechanisms. After the breaker is locked open, it may be manually reset such as by the use of the conventional disconnecting switch pole.

My invention will be more fully understood by reference to the following specification and the accompanying drawings wherein Fig. 1 is a sectional side view of a preferred embodiment of my circuit interrupter, Fig. 2 is a detail view of the lockout mechanism as it is about to lock the interrupter in open position, Fig. 3 is a view of the same mechanism in the locked-out position, Fig. 4 is a detail view showing how the lockout mechanism is reset, Fig. 5 is a plan view of a concavo-convex bimetallic element, the operation of which will be described below, and Fig. 6 is a detail view of a modification of the lockout mechanism as it appears when my circuit interrupter is in the locked-out position.

In Fig. 1 a preferred embodiment of my improved circuit interrupter is shown and designated as a whole by the numeral 1. The circuit interrupter is enclosed in a casing comprising a steel tank 2 having an insulating lining 3. The tank is cylindrical in shape and is normally positioned with its axis vertical. A vented inner insulating cylinder 4 is provided, which is of smaller diameter than lining 3. In cylinder 4, exhaust vents 5 are appropriately located for extinguishing an electric arc as will be further explained below. Two relatively movable contacts 6 and 7 are immersed in an arc extinguishing and insulating liquid such as oil, the level of which is indicated at 8. The contacts 6 and 7 are supported on thermally responsive bimetals 9 and 10 respectively, each of said bimetals having a concavo-convex form for the purpose of giving a snap action. Bimetal 9 is normally concave upward and bimetal 10 is concave downward so that contacts 6 and 7 are closed. The structure of bimetal 9 is shown in more detail by a plan view in Fig. 5. Bimetal 10 is substantially identical to 9.

Bimetal 9, which supports contact 6, is itself supported by means of a bolt 11 on an insulating partition 12 which is in turn positioned between an annular shoulder 13 extending radially inwardly from the inner surface of vented cylinder 4, and an insulating spacing cylinder 14 within cylinder 4. To the lower end of bolt 11 an in-

coming conductor 15 is attached. Bimetal 10 is fastened by means of a cap screw 41 to a piston 16 which is adapted to move vertically within the bore of cylinder 4. Piston 16 is normally biased by gravity to the lowermost position against shoulder 13 within cylinder 4. Within piston 16 is a chamber 16a which is partially filled with metal pellets 17. The weight of the piston may be adjusted as desired by changing the number of metal pellets 17. Thus the operating characteristics of the breaker may be adjusted, as will be more fully explained below. Since the support partition 12 for bolt 11, bimetal 9 and contact 6, and piston 16, which supports bimetal 10 and contact 7, are both normally positioned against shoulder 13, the axial length of shoulder 13 determines the normal contact spacing. Cylinder 4, partition 12, and piston 16 enclose a chamber 24 containing the contacts 6 and 7, their supporting members, and insulating fluid such as oil. Bimetal 10 is connected to piston 16 through a tube 18 of electrical resistance material, such as an alloy consisting of nickel and chromium, which extends through the center of piston 16, the purpose of which will be explained below. Tube 18 is surrounded by an asbestos heat insulating tube 40. At the upper surface of piston 16, outgoing conductor 23 is connected to the upper end of resistance tube 18 through a piston cover plate 16b. Thus, the electrical circuit through the circuit interrupter is through conductor 15 to bolt 11, through bimetal 9, contacts 6 and 7, bimetal 10, resistance tube 18, and outgoing conductor 23.

Under operating conditions my circuit interrupter is normally at rest in the position shown in Fig. 1. If an excessive electrical current is conducted through the interrupter, bimetals 9 and 10 are heated thereby and one or both of these bimetals snaps into the position shown with dotted lines in Fig. 1. These bimetals will snap because of their concavo-convex, or dished, shape, the concavity of said bimetals reversing as they snap so that after snapping open, bimetal 9 is concave downward and bimetal 10 is concave upward. When either bimetal 9 or 10 snaps, contacts 6 and 7 are thereby separated by a small gap, thus causing an electric arc between them. The oil in the immediate vicinity of the arc is thereby heated and vaporized, creating a pressure within chamber 24. The vapor is generated very quickly and the pressure produced thereby is not dissipated immediately through the lower vent 5, but forces piston 16 upwardly until it reaches a stop 36, or until contacts 6 and 7 are separated to an extent sufficient to extinguish the arc, after which the pressure subsides. Stop 36 may be provided with a resilient buffer (not shown) to absorb the shock of stopping piston 16. The movement of the vapor through vents 5 to exhaust the pressure within compartment 24 assists in extinguishing the arc because the ionized gases through which the arc is passing are moved toward vent 5 and the arc itself is, therefore, moved in that direction and thereby lengthened, and relatively cool, unvaporized oil is also forced between the arcing contacts in the path of the arc.

When the arc is extinguished, piston 16 returns to the position shown in Fig. 1 under the bias of its own weight. After a predetermined time, bimetals 9 and 10 both lose the heat acquired in the original overload, and snap back from the position shown with dotted lines in Fig. 1 to the position shown with solid lines. Thus,

the circuit interrupter is reclosed after a predetermined period of time during which the condition in the circuit causing the excess current may be corrected. If upon the reclosure of contacts 6 and 7 the fault or overload condition is still present, the circuit interrupter will repeat the previous interruption cycle. A small pressure relief hole (not shown) may be provided in the upper portion of casing 2 to relieve oil pressure due to repeated interruptions.

After a number of these interruption cycles the following structure becomes operative. Within the electrical resistance tube 18 on piston 16, a lockout bimetal 19 is fastened by rivets 39 so that heat generated by the electric current in resistance tube 18 may be thermally conducted into bimetal 19. Bimetal 19 extends upwardly beyond the top of piston 16, and at the upper end thereof is a latch member 20. A reset shaft 21 of triangular cross-section is rotatably mounted horizontally in the upper portion of casing 2 in a position where said shaft may be engaged by latch member 20 when piston 16 is in its elevated position and bimetal 19 is in its deflected position as shown dotted in Fig. 1. This shaft, or its equivalent in this latch-engaging function, may sometimes be hereinafter referred to as a latch-engaging member when latch member 20 thus engages reset shaft 21, as shown in Fig. 3, the circuit interrupter is locked open. Bimetal 19 is not deflected sufficiently to cause latch member 20 to engage reset shaft 21 until after a predetermined number of the circuit interruptions previously described. When such a degree of deflection of bimetal 19 is obtained, upon the next elevation of piston 16, latch member 20 engages the lower surface of reset shaft 21 as shown in Fig. 2 and bimetal 19 is thereby deflected to the right, allowing the latch member 20 to pass upwardly past reset shaft 21. This latch then engages the upper surface of such shaft when piston 16 begins its return stroke.

At one end of reset shaft 21 is a reset arm 22 by which the shaft may be rotated manually by use of a disconnect hook or switch pole 37. When my circuit interrupter is once locked in the open position, it will remain in this position until a maintenance employee uses switch hook 37 to rotate reset arm 22 to rotate reset shaft 21 to release latch member 20. Before this occurs bimetal 19 has cooled sufficiently that the bimetal will be biased to return to its normal vertical position when latch 20 is released from reset shaft 21. This release action is shown in Fig. 4. Upon such release, piston 16 descends to its original position and contacts 6 and 7 again close, thus re-establishing the original circuit through the interrupter.

In certain applications of my invention my circuit interrupter may be subjected to mechanical shocks which would tend to disengage latch 20 from the reset shaft 21. I may, therefore, use an alternative structure shown in Fig. 6 wherein the shaft or pivot 21 is shifted nearer to the center of reset arm 22 in order to reduce the tendency of this arm to rotate under shock conditions. Latch 20, in this embodiment, has been changed in shape to have a more positive retaining action in cooperation with a separate latch engaging member 43.

On the descent of piston 16, it may occur that oil will be entrapped in chamber 24. However, this oil may be displaced by the piston and the oil level adjusted by reason of an orifice 38 through resistance tube 18 through the center of the pis-

ton. An orifice 42 through the center of cap screw 41 is also provided for this purpose.

Other pressure-generating means responsive to the heat of the arc between contacts 6 and 7 as they initially separate may be used in place of the oil which is described above. For example, certain solid insulating materials such as hard fiber or methylmethacrylate emit pressure-generating gases in response to heat. In the circuit interrupter of my invention, although such a structure is not shown, the arcing chamber 24 could be lined with such a material which would thus provide the pressure-generating function of the oil in the embodiment shown and make it possible for my interrupter to be of the dry type.

The use of such a solid gas-producing insulating material in electric circuit interrupters is shown, for instance, in Patent 2,458,317, issued to Dell K. Tower and Benjamin S. Beall, III, and assigned to the same assignee as the present application.

In order to prevent rotation of piston 16 as it reciprocates and thus to avoid misalignment of arms 9 and 10 and contacts 6 and 7, a radially inwardly extending rib 34 is provided in the wall of cylinder 4 and a slot 35 in the circumference of piston 16 is provided to accommodate this rib.

Flexible turns 29 in conductor 23 allow for relative movement between the ends of conductor 23 which is necessary by reason of the reciprocal movement of piston 16.

My complete circuit interrupter structure is adapted for mounting as a unit on a wooden cross arm of a conventional low voltage transmission pole. The steel tank 2 is provided with cover structure 25 suitably secured, as by screw studs 26 to the breaker tank. The cover structure is provided with downwardly extending lateral extensions 27 in which are mounted the lead-in insulating bushings 28 for the line conductors 15 and 23. The insulators are suitably mounted and sealed, as at 30, so as to seal the breaker against moisture, etc. A cover plate 31 is sealed and secured, as at 32, to the cover structure for facilitating inspection. A pair of supporting lugs 33 are secured to the cover structure so that the breaker as a unit may be suspended from or slung beneath the pole cross arm.

While I have described and illustrated a preferred embodiment of my invention, it should be understood that I do not intend to be restricted solely thereto but I do intend to cover all modifications thereof which would be apparent to one skilled in the art and which come within the spirit and scope of my invention.

What I claim as new and desire to secure by Letters Patent of the United States is:

1. An electric circuit interrupter of the reclosing type including an enclosed container and a temperature responsive gas generating substance and a reciprocable piston within said container, a thermally responsive current carrying member attached to and movable with said reciprocable piston, separable contacts, one of which is attached to said thermally responsive current carrying member and adapted to be separated thereby to initiate an electric arc to heat said temperature responsive gas generating substance to thereby generate a gas to cause a pressure within said container which forces the reciprocable piston and the attached thermally responsive current carrying member upward to increase the separation between the respective contacts and interrupt the electric circuit, said container having an exhaust opening in the lower end

thereof to allow the escape of the gas for said piston to return to its original position, said thermally responsive member also returning to its original position to re-establish the electric circuit after a predetermined time delay interval during which said thermally responsive member returns to substantially its former temperature, and a thermally responsive lockout member adapted after a predetermined number of circuit interruptions to retain said piston in the elevated position.

2. An electric circuit interrupter of the reclosing type including an enclosed container partially filled with a vaporizable insulating liquid, a reciprocable piston within said container, a thermally responsive current carrying member attached to and movable with said reciprocable piston, separable contacts one of which is attached to said thermally responsive current carrying member and adapted to be separated thereby to initiate an electric arc to vaporize a portion of the insulating liquid to cause a pressure within said container which forces the reciprocable piston and the attached thermally responsive current carrying member upward to increase the separation between the respective contacts and interrupt the electric circuit, said container having an exhaust opening in the lower end thereof to allow the escape of the vapor for said piston to return to its original position, said thermally responsive member also returning to its original position to re-establish the electric circuit after a predetermined time delay interval during which said thermally responsive member returns to substantially its former temperature, a thermally responsive lockout member adapted after a predetermined number of circuit interruptions to retain said piston in the elevated position.

3. An electric circuit interrupter of the reclosing type comprising a casing, coacting relatively movable contacts supported on current carrying snap-acting bimetallic elements and arranged to initially separate within an insulating liquid in the lower part of said casing when said bimetallic elements are heated by an overload current, a piston within said casing vertically reciprocable between a lower position in which the interrupter is normally closed and a raised position in which the interrupter is open, one of said bimetallic elements being supported on said piston, said piston being biased downwardly by its own weight and adapted to rise vertically under the force of oil vapor generated by an electric arc which occurs as said contacts initially separate to thereby cause a further separation of said contacts and an extinguishment of said arc, the initial separation of said contacts being maintained upon the return of said piston to its original position to maintain the circuit interruption for a predetermined time delay period, a bimetallic lockout element supported on said piston and having a latch member on the end thereof, a latch engaging member, said latch member being adapted to engage said latch engaging member under the influence of said lockout element after a given number of circuit interruptions initiated by said bimetallic elements to retain said piston in the raised position, said latch engaging member being rotatable to release said latch member.

4. An electric circuit interrupter of the reclosing type comprising a casing, coacting relatively movable contacts supported on current carrying snap-acting bimetallic elements and arranged to initially separate within an insulating liquid in

the lower part of said casing when said bimetallic elements are heated by an overload current, a piston within said casing vertically reciprocable between a lower position in which the interrupter is normally closed and a raised position in which the interrupter is open, one of said bimetallic elements being supported on said piston, said piston being biased downwardly by its own weight and adapted to rise vertically under the force of oil vapor generated by an electric arc which occurs as said contacts initially separate to thereby cause a further separation of said contacts and an extinguishment of said arc, the initial separation of said contacts being maintained upon the return of said piston to its original position to maintain the circuit interruption for a predetermined time delay period, a bimetallic lockout element supported on said piston and having a latch member on the end thereof, a reset shaft, said member being adapted to engage said reset shaft under the influence of said lockout element after a given number of circuit interruptions initiated by said bimetallic elements to retain said piston in the raised position, said reset shaft being rotatable to release said member.

5. An electric circuit interrupter of the reclosing type comprising an oil filled vertical cylindrical container, a vented cylindrical container within said first cylindrical container, a piston reciprocable within said vented cylindrical container, separable electrical contacts, two bimetallic thermally responsive current carrying trip elements respectively for the support of each of said contacts, one of said elements being supported at the bottom of said vented cylindrical container and the other of said elements being supported on the lower portion of said reciprocable piston, said elements being adapted, when heated by an overload current, to snap said electrical contacts apart, thus initiating an electric arc the heat of which vaporizes a portion of said oil and thereby generates a pressure which raises said reciprocable piston, thereby further separating said separable contacts, thus interrupting said arc by the lengthening thereof and by the interposition of oil in the path thereof by virtue of the exhaustion of said vapor through the vents

of the vented cylindrical container, said piston being further adapted to descend to the original position upon the exhaustion of said vapor, said piston being of a hollow construction and including a filler of an adjustable quantity of metal pellets for added weight to accelerate said descent at a selected rate, the separation of said separable contacts being maintained by said thermally responsive current carrying trip elements for a given time after the descent of said piston until said elements attain a reduced temperature, said interrupter being adapted to repeat the above interruption cycle a number of times should said overload current persist, a thermostatic lockout bimetal attached to the upper portion of said piston and an electric current carrying resistance element associated therewith and adapted to heat said bimetal upon the occurrence of an overload current to thereby cause said bimetal to deflect, a latch member at the end of said bimetal and a rotatable reset shaft adapted to be engaged thereby when said bimetal has been deflected and when said reciprocable piston is in the raised position, said bimetal being deflected sufficiently for this purpose only when the overload current condition persists after a predetermined number of interruption cycles, the upper surface of said latch member and the lower surface of said reset shaft having slanted contours which are adapted to enable said latch member to be deflected from said shaft, on the upward stroke of said piston, said latch member then being adapted to engage said shaft on the downward stroke of said piston to retain said piston in the raised position, the upper surface of said shaft and the lower surface of said latch being slanted to prevent subsequent disengagement after said bimetal cools and thereby becomes biased towards the undeflected position, and means for rotating said shaft whereby the upper surface of said shaft may be rotated toward said bimetal to reverse the slant of the upper surface of said shaft and thereby release said latch to allow said piston to descend, reclosing said interrupter.
